UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 21, 1921. Serial No. 479,190.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening devices for typewriting machines. The invention is of the same general type as that disclosed in the co-pending application of B. C. Stickney, Serial No. 429,617, filed December 10, 1920 (now Patent No. 1,519,224, 15 dated December 16, 1924), and comprises a sound-deadening casing or hood for enclosing the noise-producing parts of a typewriting machine, while the keys and other parts of the machine used in its operation project from the casing or hood.

The casing is so constructed that it can be slid upon a typewriting machine from the front thereof, the front of the machine entering the rear of the casing, which, for 25 this purpose, is provided with a large insertion opening. When the machine is completely within the casing, the rear opening of the latter is closed, thus completely enclosing the machine, to prevent the escape 30 of sound.

A feature of this invention lies in the novel, simple, and effective closure means for the opening in the rear wall of the casing, said means being in the form of a door 35 mounted so that it may be readily swung to open position to permit the casing to be applied to the machine and locked in closed position.

Another feature of this invention is the 40 construction of a front wall of the casing to cover almost completely the front plate of the typewriting machine, and thus avoid the necessity of providing sound-deadening means for said front plate in addition to 45 said front wall. For this purpose, the front wall of the casing is provided with an opening just large enough to permit the forward extension of the typewriter frame, in which are mounted the banks of keys, or, in other 50 words, the keyboard section of the machine, to project therethrough.

A further feature of this invention is the construction of the front wall of the casing, so that said wall may be brought flush 55 against the front plate of the typewriting

machine without removing the ribbon-color shift-key. For this purpose, a hole is provided in the front wall of the casing large enough to clear the ribbon-color shift-key.

Provision is made for a slot at the front 60 of the casing, through which various operating levers and finger-pieces, such as the line-space handle, carriage-return finger-piece, and carriage-release-lever extend, so that the machine may be operated from outside of the casing. Means are provided for closing all of the slot not occupied by the levers and finger-pieces, in order to prevent the escape of sound, said means comprising 65 cooperating cushions in the form of folds 70 of sound-deadening material. It is a feature of this invention to provide means to increase the resiliency of the folds of sound-deadening material to cause them to return readily, said means comprising reinforcing 75 layers of horse-hair as backings or linings for the folds.

Other features and advantages will hereinafter appear.

In the accompanying drawings,

Figure 1 is a front view of the sound-deadening casing forming the subject of this invention, applied to an Underwood standard typewriting machine.

Figure 2 is a perspective view from the 85 rear, showing the closure means for the opening in the rear wall.

Figure 3 is a detail of a cushion, comprising a fold of sound-deadening material used for closing the front slot and a backing of 90 horse-hair for said material for increasing the resiliency of the material.

Figure 4 is a side view, vertically sectioned, of the device, as shown in Figure 1.

Figure 5 is a plan view of the device as 95 shown in Figure 1, the cover having been removed to display the interior of the casing.

The Underwood standard typewriting machine comprises a main frame 10 and a 100 forward extension 11 of the main frame, in which are positioned banks of keys 12, said keys, when depressed, operating type-bars 13 to cause types 14 carried thereby to strike against a platen 15 at the printing point. Said platen is fixed upon a shaft or axle 16, journaled in the end walls 17 of a platen-frame 18, mounted in a carriage 20 having letter-feeding movement on a front rail (not shown) and a rear rail 21 fixed to the 110

main frame 10. The platen may be rotated by knobs or finger-wheels 25 fixed to the ends of shaft 16 or by the usual line-space mechanism, of which the line-space lever or handle 26 and slide 27 are shown. The carriage is provided with the usual pointer 28 operating over scale 29, and may be returned to the right by a finger-piece 30 fixed thereto, or released from the letter-feeding mechanism by a carriage-release-lever 31.

For deadening the sounds arising in the typing operation, there is provided a sound-deadening casing or hood comprising a body part 40 and a cover part 41. The body 40 comprises a front wall 42, side walls 43, and a rear wall in the form of two end sections 44, spaced apart to provide a large opening 44^a sufficient to permit passage of the typewriting machine therethrough and into the body part of the casing, said rear wall being of greater height than the height of the typewriting machine. Assuming that the typewriting machine rests upon a base, such as 50, the casing or hood may be slid along the base and onto the machine from the front thereof, as in my application, Serial No. 478,231, filed June 17, 1921. The cover 41 is at this time raised sufficiently to clear the line-space lever 26, the forward extension 11 of the typewriting machine entering the rear of the casing through the opening 44^a between end sections 44, and the casing being moved rearwardly until the front of the main frame 10 contacts with positioning abutments 51 fixed to the front wall 42, the forward extension 11 projecting through an opening 52 in the front wall 42. Said opening 52 is just large enough to permit the forward extension of the typewriter frame to project therethrough, the front wall of the casing covering substantially all of the remaining portion of the usual front plate 52^a of the typewriter frame, thus avoiding the necessity of lining with a sound-deadening material the front plate, which is usually of thin metal capable of transmitting sounds. Provision is, however, made of sound-deadening material in the form of a sheet 42^a between the front plate 52^a of the typewriter frame and the front wall 42 of the casing. Said sheet 42^a may be attached to the rear face of the front wall 42 to serve as a lining therefor.

To permit the ribbon-color shift-key 53 to project outside of the casing at the front thereof, the front wall 42 is provided with an opening 54 large enough to permit the entire shift-key to project therethrough. Hitherto, it has been necessary with hoods, in which the front plate is integral with the casing, to remove the ribbon-color shift-key from its shaft when the casing was to be applied, and again attach it to the end of the shaft after applying the casing, the shaft projecting through a small hole in the front

wall. The opening 54 thus avoids the necessity of removing the shift-key when the casing is applied. An opening 55 is provided in the front wall 42, through which the line-lock release-key 56 projects and may be operated from outside the casing.

It will thus be seen that, when the typewriting machine is positioned within the body part of the casing, the forward extension or keyboard section 11, the ribbon-color shift-key, and the line-lock release-key project outside of the casing. The body part is provided with extensions 60, above which the typewriter carriage operates to the right and left. The machine is thus enclosed at all times by the body part at the front and sides thereof, but is open at the top and rear. To close the top opening, there is provided the cover 41 hinged to the end sections 44 of the body part by means of a bolt, or rod, 61 passing through alternately arranged turned-over ends 62 and 63 of a rear wall 64 of the cover and the end sections 44, respectively. The cover is thus hinged to the body part only near its ends, the lower edge of the rear wall 64 of the cover forming the upper edge of the rear wall of the body part between the end sections 44. The cover comprises a top wall or ceiling 65 extending forwardly and downwardly toward the front of the casing, side walls 66 provided with flanges 67 which rest upon ledges 68 of extensions 60, said ledges 68 being provided with embedded strips 69 of sound-deadening material, such as felt, and a front wall 70, which may be separate or formed integral with the other walls of the cover. For permitting the typewriting at the interior of the casing to be viewed when the cover is in lowered position, the top wall is provided with a transparent plate 71 suitably held, as by clamps 72, to permit withdrawal of the plate when desired.

When the cover is in closed or lowered position, there is still an opening or slot between the lower edge of the front wall 70 and the upper edge of front wall 42, through which slot project the line-space handle 26, carriage-return finger-piece 30, and carriage-release-lever 31, so as to permit ordinary operation of the machine without raising the cover. It is necessary, however, to close all of the slot not actually occupied by these finger-pieces or levers, in order to prevent transmission of sounds therethrough. For this purpose, two co-operating cushions 74 and 75 are provided, said cushions comprising folds of sound-deadening material, such as plush, felt, or soft leather, the two-ply edges of each fold being clamped between two bars 76 and 77, fastened together by bolts 77^a to form single units which are mounted on the lower edge of front wall 70 and upper edge of front wall 42, respectively, by screws 77^b passing

through holes 77^e so that the folds contact. It has been found desirable to increase the resiliency of the cushions so as to return to normal more readily when distorted by the

5 passage or operation of the various finger-pieces and levers. For this purpose, the folds of sound-deadening material are each backed or lined with a layer of material 78 composed of horse-hair (see Figure 3), the 10 edges of which are clamped with the edges of the folds of the cushions between the bars 76 and 77.

The typewriting machine is thus completely enclosed at the front, sides, and top, 15 but there still remains the insertion opening at the rear between end sections 44, the base 50 and the lower edge of wall 64, through which opening the machine entered the casing. For closing this opening, there is provided 20 a closure member or door in the form of a cover-plate 80, having turned-over end members 81 forming bearings which are alternately arranged with the similar end members 63 of the cover, the rod 61 passing 25 through members 62, 63 and 81 to hinge the cover to the body and to hinge the cover-plate to the cover part. The height of the cover-plate is the distance from the base to the hinge, and its width is greater than the 30 width of the opening, so that it overlies the end sections 44. To lock the cover-plate in lowered position, there is provided a catch 85 adjacent each side edge of the cover-plate and engaging in a slot 86 in the underlying 35 end section 44, said catch being withdrawable from said slot when slid upwardly by means of a finger-piece 87 on a bolt 88, to which said catch is fixed, said bolt being guided in its movements by brackets 89 fixed 40 to the cover-plate, the upward movement of the bolts being limited by projections 88^a which engage the lower brackets 89. The cover-plate carries abutments 90, which, together with the abutments 51, hold the machine against movement within the casing, 45 the machine having been previously positioned within the casing by abutments 51.

The sound-deadening casing, as described above, is preferably of metal, such as iron, 50 and the main metallic parts thereof may be formed in three sections, that is, cover, body part, and cover-plate. Each section may be built up or cast to form a unit. To support 55 the casing more firmly on the base, the body part may have inturned flanges 91 at the lower ends of the walls, and preferably formed integral with the walls.

It will be understood that, by hinging 60 the cover-plate on the casing, it may readily be swung into closing position, and the necessity of locating it relatively to the casing and the possibility of its becoming misplaced, which may be experienced with a detachable cover-plate such as shown in my application, 65 Serial No. 478,231, above referred to,

and in my application Serial No. 466,820, filed May 4, 1921 (now Patent No. 1,519,645, dated December 16, 1924), are thus eliminated.

The casing may be lined with any suitable 70 sound-deadening material, such as felt.

Variations may be resorted to within the scope of the invention, and portions of the improvements may be used without others.

Having thus described my invention, I 75 claim:

1. A sound-deadening casing for a typewriting machine having a keyboard extension and a forwardly-extending key above said keyboard extension, said casing having 80 at its front an opening just large enough to receive said extension, a second opening to receive said key and locating means to engage the front of the machine and assist in positioning the same in the casing, said casing also having an opening in its rear to receive the typewriting machine therethrough into position with the extension projecting through the front opening, and a door 85 hinged at its upper edge to the casing proper 90 for closing the rear opening and pressing the machine against said locating means, to cause the front of the machine around said key to co-operate with the front of the casing to prevent the escape of sound through the 95 corresponding opening in the casing.

2. A sound-deadening casing for a typewriting machine, said casing comprising a body portion having side members fixed thereto and provided with overhanging lateral extensions to accommodate the travel of the typewriter-carriage, said side members being spaced apart at the rear to provide an opening of sufficient width to permit the passage of the machine therethrough, a cover 100 hinged at its rear edge on said side members at such a height as to permit the passage of the machine thereunder, and a door to close the rear opening of the body portion, said door being hinged to said side members to 105 swing about the same axis as said cover.

3. A sound-deadening casing for a typewriting machine having a keyboard extension, said casing comprising a body part, a cover, said body part comprising a front wall of unitary construction having an opening extending upwardly from the lower margin of said wall but large enough to permit said extension to be passed therethrough, locating means to engage the front of the machine and a rear wall formed by two laterally-spaced end sections, the space between the end sections being sufficient to permit the passage of the typewriting machine therethrough and into said casing, said end sections having bearing members formed on their upper edges, a door for the opening in said rear wall, said door having bearing members at regular intervals, bearing members formed on said cover at regular inter- 115 120 125 130

vals, to alternate with the bearing members on said end sections and on said door, and a rod passing through all of said bearing members.

5 4. A sound-deadening casing for a typewriting machine having a keyboard extension, said casing comprising a body part and a cover, said body part comprising a front wall having an opening just large
10 enough to permit the passage of said keyboard extension, a rear wall formed by two laterally-spaced end sections, the space between the end sections being sufficient to permit the passage of the typewriting machine therethrough and into said casing, said cover being hinged at the rear to said end sections, a door hinged at its upper edge to said casing for closing the space between said end sections, said door overlying
15 said end sections, and means for locking said door in closed position comprising a latch at each side of said door, each of said end sections having an opening through which the respective latch passes to engage
20 the body part, said latches being shiftable to release the door.

5. In combination, a sound-deadening casing, a typewriting machine having a keyboard extension and fitted within said casing, said machine comprising a body from which a shaft projects forwardly, an enlarged finger-piece on the front of said shaft, said casing having a fixed front wall of unitary construction covering the front of the
30 machine body and provided in its lower portion with an opening through which said keyboard extension is passed from the rear and an opening to permit said finger-piece to project therethrough as the machine is
35 inserted in the casing from the rear of the latter, sound-deadening material between the machine and the front wall of the casing to close the opening between said machine and the edges of the opening in said front wall around said finger-piece, said casing having a rear wall having an insertion opening of sufficient size to receive the machine, a door for said insertion opening, and locating means movable to engage and locate the
40 machine in proper relation with said front wall of the casing.

50 6. A sound-deadening casing, a typewriting machine having a keyboard extension and also having a front plate above said extension, and also having a ribbon-color shift-key and a line-lock release-key at the front of said front plate, said casing having a fixed front wall of unitary construction above the keyboard and forward of said front plate and provided with an opening just large enough to receive said keyboard extension when inserted from the rear, and also provided with openings to accommodate the ribbon-color shift-key and the line-lock release-key, and sound-deadening ma-

70 terial between said front plate of the machine and the front wall of the casing to close the openings between the front plate and the edges of the front wall around the openings for the ribbon-color shift-key and the line-lock release-key.

75 7. A sound-deadening casing for a typewriting machine having a keyboard extension, a traveling carriage and an operating finger-piece projecting forwardly from said carriage, said casing having a fixed front wall of unitary construction provided with an opening extending upwardly from the lower margin of said wall but of sufficient size to permit the keyboard extension to be inserted from the rear, locating means to be engaged by the front of the machine in such insertion, said casing also having an insertion opening in its rear wall large enough to permit the passage of the machine, a door for said insertion opening hinged at its upper edge to the casing proper, and a cover for the casing co-operating at its forward edge with the upper edge of the front wall to provide a slot along which said finger-piece may travel with the carriage and swingable upwardly to permit the insertion of the finger-piece into said slot when the machine is inserted into the casing from the rear, said cover being mounted on the casing so as to swing about the same axis as said door.

8. A sound-deadening casing for a typewriting machine having a keyboard extension and a forwardly-projecting key thereabove, said casing comprising a front wall and a rear wall, said front wall having an opening to furnish a close fit for said extension and an opening to receive said key, and said rear wall having an opening to permit the machine to be inserted into the casing from the rear, and the extension and the key to be passed through the openings in the front wall, abutments on the front wall to engage the machine to locate the casing and the machine relatively to each other, a pivoted door to close the opening in the rear wall, abutments carried by said pivoted door to oppose the abutments on the front wall and clamp the machine in position in said casing, and latching means to lock said door in closed position.

9. A sound-deadening casing for a typewriting machine having at its front a key movable in a vertical plane parallel to the front of the machine, said casing comprising a front wall integral with said casing and having an opening to clear the keyboard section of the machine, a separate opening to clear said key to avoid interference in assembling the machine and casing, and a lining of sound-deadening material to co-operate with the front of said machine around said openings to assist in deadening the sound.

10. In a casing for a typewriting machine, including a frame and a keyboard, the combination of a body-part and a cover, the body-part having a front wall with an opening therein to permit the passage of the keyboard therethrough, and having a rear wall with an opening therein to permit the passage of the typewriting machine therethrough, a swingable door arranged to close 5
5 said rear opening, and co-operating opposed, clamping means mounted on the front wall and on said swingable door to engage said machine and clamp it into operative location in said casing.
15. 11. A sound-deadening casing for a typewriting machine having a keyboard-extension, said casing comprising a body-part having a front wall of unitary construction, with an opening, extending downwardly below the top margin of said front wall, large enough to receive said extension, and locating means to engage the front of the machine and assist in positioning said machine in the casing, said casing also having an 20
20 opening in its rear to permit the passage of the typewriting machine therethrough into said casing with the extension of said machine operably projecting through the opening in said front wall, a door being pivoted near its top to the casing-body arranged to close the rear opening of the casing, press against the machine-frame and locate said machine in the casing, and a cover being hinged to said casing above the height of 25
25 the typewriting machine, arranged to swing about the same axis as the door, to give access to work in the machine.
12. In a casing for a typewriting machine, including a frame and a keyboard, the combination of a body-part and a cover, the body-part having a front wall with an opening arranged to permit the keyboard to be passed therethrough, and having side walls, each of which is provided at its upper portion with an outwardly-disposed lateral extension, arranged to permit the travel of a typewriter-carriage therein in its opposite extreme positions, the cover being swingably mounted on said side walls and arranged to close the top of said casing and said extensions of said walls, rear wall-portions spaced apart and arranged at the op- 30
30
- posite ends of said casing to close the rear of said extensions, separated by a rear opening in said casing, and a door, swingably mounted at the rear of said casing, arranged to close the opening between said rear wall-portions, and in combination with said rear wall-portions, said extensions and cover, when the latter is closed, forming a closed 35
35 chamber for the movement of the typewriter-carriage.
13. In a casing for a typewriting machine, including a frame and a keyboard-extension, the combination of a body-part and a cover, said body-part being provided with a front wall of unitary construction having an opening below its top margin to permit the passage of the keyboard-extension therethrough, end walls connected to said front 40
40 wall, extending rearwardly and provided with outward laterally-extending, upper portions to permit the travel of a typewriter-carriage to its extreme positions of movement, said casing having an open top 45
45 and an open back, a door to close the opening in said back, a cover to close the opening in said top, and a supporting axis mounted on the opposite ends of said casing and spanning the opening in the back, said door 50
50 and said cover being swingably mounted on said axis, said cover being arranged for opening to permit the insertion of said typewriting machine into said casing through said top opening, and said door being swingably mounted to permit said typewriting machine to be installed in said casing, through said rear opening.
14. The combination of a typewriting machine, a sound-proof cabinet in which the machine is fitted, said cabinet including a top cover and a rear door hinged to each other for movement independently of each other and of the cabinet, said cabinet having ends hinged to and closed by said cover, 55
55 said ends including the side walls of the cabinet and also including the overhanging portions accommodating the travel of the carriage of the typewriting machine.

JOHN WALDHEIM.
